IV

Fig. 5.

Fig. 5A.

Fig. 1 is a plan view of a full panel of plastic sheet material embodying the new design, taken on a reduced scale;

Fig. 2 is a view of the portion of Fig. 1 within the solid line frame II of that figure on a full size scale;

Fig. 2A is a cross-sectional view taken on the line 2A—2A of Fig. 2;

Fig. 3 is a view of the portion of Fig. 1 within the dotted line frame III of that figure on a full size scale;

Fig. 3A is a cross-sectional view taken on the line 3A—3A of Fig. 3;

Fig. 4 is a view of the portion of Fig. 1 within the solid line frame IV of that figure on a full size scale;

Fig. 4A is a cross-sectional view taken on the line 4A—4A of Fig. 4;

Fig. 5 is a view of the portion of Fig. 1 within the dotted line frame V of that figure on a full size scale; and

Fig. 5A is a cross-sectional view taken on the line 5A—5A of Fig. 5.

I claim:

The ornamental design for a panel of plastic sheet material or similar article, substantially as shown.
